UNITED STATES PATENT OFFICE.

ALEXANDER FISCHER, JR., OF CINCINNATI, OHIO.

MOP.

1,086,660.

Specification of Letters Patent. Patented Feb. 10, 1914.

Application filed March 19, 1913. Serial No. 755,270.

To all whom it may concern:

Be it known that I, ALEXANDER FISCHER, Jr., citizen of the United States of America, and resident of Cincinnati, county of Hamilton, and State of Ohio, have invented certain new and useful Improvements in Mops, of which the following is a specification.

This invention relates to improvements in 10 mops and to mop-wringing devices.

An object of the invention is to produce a simple, cheap and effective mop, and simple, effective, and easily operated means for wringing the mop. These and other objects 15 I attain in an apparatus embodying the features herein described and illustrated.

In the drawings accompanying and forming a part of this application, Figure 1 is a side elevation of a mop embodying my invention, and equipped with a wringing device which forms a part of my invention. The wringing device is shown in the inoperative position, or the position to which it is moved while the mop is being used.

20 Fig. 2 is a fragmental side elevation showing the separate portions of the wringing device moved apart, preparatory to moving them to an operative or mop-wringing position, relatively to the mop. Fig. 3 is a

25 fragmental elevation of the mop shown in Fig. 1, and together with Fig. 1, illustrates the means employed for securing the mop portion to the handle portion. Fig.

30 4 is a side elevation of a metal loop which 35 is employed in the operation of securing the strands of yarn together, which form the mop portion. Fig. 5 is a view corresponding to Fig. 4 and shows the position to which the loop is twisted, for the purpose 40 of permanently locking the strands of yarn to it. Fig. 6 is a sectional view along the

line 6—6 of Fig. 1, and discloses the means 45 employed for holding the separate portions of the wringing device in the inoperative position, with relation to the handle portion of the mop. Fig. 7 shows the mop and the wringing device in the relative positions 50 which they occupy during the operation of wringing out the mop portion. Fig. 8 is a detail sectional view illustrating one of the wringing rollers applied to its supporting rod and Fig. 9 represents the lower end 55 of the mop handle adapted to receive the mop holder shown in Fig. 5.

Referring to the drawings: The mop portion, illustrated, consists of a plurality of

strands of yarn 8, or other suitable material, which are secured together by means of a metallic loop 9, and which are then secured in place on the handle portion 10, of the 60 mop, by means of the loop 9. During the operation of forming the mop, the separate strands of yarn 8, are placed in the loop 9, so that each strand is suspended by the loop at a point substantially midway between 65 its ends. After all the strands are in place, and are drawn tightly against the lower or closed end of the loop, the loop is twisted a whole turn, as shown in Fig. 5, while its open ends are held firmly, to prevent them 70 from moving relatively to each other. The twisting of the loop permanently binds the strands 8 together and forms the assembled 75 mop portion. The handle of the mop is provided near its lower end with apertures 11—11, each of which is adapted to receive one of the ends of the metal loop 9. The lower end of the mop is also provided with a notch 12, which is adapted to receive the twisted portion of the metal loop 9 and to 80 rigidly hold it in place relatively to the handle 10, when the ends of the loop are inserted into the apertures 11—11. It will be understood that, while the resiliency of the metal loop may be sufficient to rigidly 85 lock the mop portion to the handle, that additional means may be employed for positively securing the bent over ends 13, of the loop, in place within the apertures 11—11. With the arrangement illustrated, the en- 90 gagement of the ends 13 of the loop, with the apertures formed in the handle, rigidly secures the mop portion to the handle, and the notch 12 prevents the loop from turning, relatively to the handle portion, and 95 therefore aids in positively locking the mop in place.

The wringing device, illustrated, consists of two bars or rods 14, which are pivotally secured, by means of a bolt 15, to the handle 100 portion 10. The bolt 15, extends through an aperture in the handle portion, which is located intermediate its ends, and one of the rods 14 is located on each side of the handle portion. The pivoted ends of the 105 rods 14 are tapered by inclining their inner faces, so that the rods can be spread apart at their outer or free ends, as shown in Fig. 2. Each rod is provided with a wringing roller 16, which is rotatably mounted thereon, and which is adapted to co-operate with the roller of the other rod, during the op- 110

eration of wringing out the mop. As shown, each roller consists of a cylindrical section, which is rotatably mounted on collars 17 and 18, rigidly mounted on the rod. The rollers 16 are so mounted on their mounting rods that the ends of the rods project beyond them and form handle portions 18', which may be employed during the operation of wringing the mop and which may 10 also be employed during the operation of using the mop. A chain 19 is employed, in the illustrated embodiment of my invention, to limit the spread between the rods 14, and it is preferably of such length that 15 the mop can be conveniently introduced between the rollers, when the rods are spread apart.

The outer end of the mop handle is provided with diametrically located and longitudinally extending grooves 21, which are adapted to receive the rods 14 and to lock them against motion, relatively to the handle, when they are pressed inwardly against the handle. The rods in this position form, in effect, an extension for the handle, which is preferably shorter than the handles of ordinary mops. When it is desired to wring out the mop portion, the rods 14 are released and allowed to move 20 to their spread position, as shown in Fig. 2. This frees them from the grooves 21, and they may then be turned about the bolt 15, to the position illustrated in Fig. 7, in which the rollers 16 are located in such a 25 position that the mop portion may be inserted between them. During the wringing operation, I preferably turn the rods 14 downwardly over the mop to the position illustrated in Fig. 7, and either support 30 them on, or locate them above, a bucket or other receptacle 22, which is employed for the purpose of wetting the mop. The mop handle is then turned, relatively to the rods 14, so that the mop can be moved up or 35 down between the rollers and into and out of the bucket. During the wringing operation, the handle portions 18' of the rods 14 are moved together, so as to force the rolls 16 against the mop portion, and the mop 40 is then drawn upwardly between the rollers 16, while the handles are held in this position. During the wringing operation, I find that the rods 14 can be conveniently held in the wringing position by the right hand, 45 while the handle portion 15 is grasped by the left hand of the operator and moved upwardly relatively to the rollers 16. During this operation, the end of the handle portion 10 can be conveniently steadied by 50 the foot of the operator, by forcing it against the floor. It will, of course, be understood that the mop can be wrung as many times as desired, and for this reason the rods 14 need not necessarily be supported on the upper edge of the bucket dur-

ing the wringing operation. After the mop has been wrung out, the rods 14 are turned about their pivotal point, to the position shown in Fig. 2, and they are then moved into the grooves 21, for the purpose of 70 forming an extension for the handle 10, by drawing the minwardly toward each other, as shown in Fig. 1.

In the drawings I have shown each collar 18 so formed that it prevents the water, 75 from the rollers 16, from running down along the rod 14. This is accomplished by increasing the diameter of the collar, so that it projects a desired amount beyond the cylindrical surface of the roller. With such an arrangement, water running down the roller will drain off of the collar 18 into the bucket 22 and will not trickle down the rods 14.

In accordance with the United States patent statutes, I have illustrated and described the preferred embodiment of my invention, but I desire it to be understood that various changes, modifications and substitutions may be made in the apparatus 90 illustrated, without departing from the spirit and scope of my invention, as set forth by the appended claims.

What I claim is:

1. In combination in a mop, a handle portion, rods pivotally mounted on the handle, and forming an extension therefor, and capable of being moved to a wringing position, with relation to the mop cloth. 95
2. In combination in a mop, a handle portion, wringer roller-carrying rods, pivotally mounted on the handle and capable of forming an extension thereof, or of being turned relatively thereto, for the purpose of moving the wringer rollers into engagement 100 with the mop material. 105
3. In combination in a mop, a handle for the mop, having longitudinally extending grooves formed therein, and wringer rods pivotally mounted on the handle and capable of being moved into locking engagement with the grooves. 110
4. In combination in a mop, a handle therefor, provided with rod-receiving grooves, rods pivotally mounted thereon, and capable of being moved into said grooves, to form an extension for the handle, or to be turned to a wringing position relatively to the mop material, and wringer rollers rotatively mounted on the rods. 115
5. In combination, a mop, a handle for the mop, having oppositely located longitudinal grooves formed therein and extending from an intermediate point of the handle to the outer end thereof, a pivot bolt 120 mounted on the handle adjacent to the inner ends of said grooves, a pair of rods pivotally mounted on said bolt, located on opposite sides of the handle and capable of being moved into locking engagement with the 125 130

grooves, to form an extension for the handle, or of being turned to a wringing position, with relation to the mop cloth, and a wringer roller mounted on each rod, between the end thereof and the pivot bolt, for engaging the mop when the rod is turned to a mop-engaging position.

In testimony whereof, I have hereunto subscribed my name this 17th day of March, 1913.
